R. Richardson Atty.

UNITED STATES PATENT OFFICE

JOHN E. OSTLINE, OF LIVERPOOL, ENGLAND, ASSIGNOR TO AUTOMATIC ELECTRIC
INC., OF CHICAGO, ILLINOIS, A CORPORATION OF DELAWARE

ROTARY LINE SWITCH

Application filed June 7, 1926, Serial No. 114,189, and in Great Britain September 28, 1925. Renewed
December 6, 1928.

The present invention relates to improvements in or relating to switches as used in telephone systems and more particularly concerns that type of switch known as a rotary line switch, that is to say, a line switch which is individual to each subscriber's line and is of the type which has a continuously forward step-by-step movement and is advanced to a normal position after use. In switches of this type it is necessary to provide means to ensure that the "cut-off" relay, which connects the conductors leading from the subscriber's station to an outgoing trunk, cannot be operated after the subscriber has hung up and the switch is returning to normal until the normal position is reached. It has been proposed to do this by providing an earth connection on the side of the cut-off relay which is not connected to the test lead or private normal coming from the connector banks.

Now when a connector makes connection with a rotary line switch, it initially performs a testing operation over this private normal by connecting battery through a "busy" relay to the private normal. Consequently, when an earth connection is provided on the side of the cut-off relay which is not connected to the test lead or private normal coming from the connector banks, a condition which occurs when the rotary line switch is restoring to normal, and provided the busy relay is off a sufficiently high resistance compared with the resistance of the cut-off relay, the cut-off relay will not energize. The busy relay is, however, arranged to operate in this circuit. However, in certain conditions it is neither convenient nor desirable to provide a test relay of specially high resistance, particularly in a rotary connector, and it is the object of the present invention to effectually prevent the cut-off relay energizing under any conditions which may occur in the connector. According to the present invention this may be effected in two ways:

The first way is to provide a direct earth connection on the private normal all the time the rotary line switch is off normal, so that only after it has returned to the normal position is the private normal free from an earth

connection and then only if the subscriber, whose line the line switch is associated with, is not initiating a call, that is to say, if he has not just lifted his receiver. By this means the line would always test busy to a connector switch until the rotary line switch had resumed its normal position.

The other alternative is to provide an open connection in the circuit of the private normal and the cut-off relay so that the private normal is disconnected from either battery or earth connection at the rotary line switch side, while the rotary line switch is returning to normal.

One advantage of this latter arrangement is that a subscriber calling a line does not receive the busy signal, but the connector remains on the line and switches through immediately the rotary line switch has reached its normal position. As only a very short interval of time elapses while the rotary line switch is returning to normal and the calling subscriber's telephone actually is disengaged and he is ready to receive another call, the short interval which elapses before the call is switched through is negligible. For this reason the invention has been solved in the two manners.

In order that the invention may be more clearly understood and readily carried into effect a detailed description of a rotary line switch according to the present invention will now be given with reference to the annexed drawings in which:

Fig. 1 shows a rotary line switch of the homing type provided with a combined guarding and homing contact bank adapted to be engaged by a single wiper.

Fig. 2 shows a rotary line switch of the homing type in which no modification is made to the homing bank, the desired result being obtained by circuit arrangements.

Fig. 3 shows a modification of the arrangement according to Fig. 1, in which the circuits are arranged to prevent the meter from operating, should the line relay be operated manually during the time the cut-off relay is energized.

A detailed description will first be given of the arrangement shown in Fig. 3. In this

figure and in Fig. 1 the construction of the bank contacts are modified. Normally the number of bank contacts provided per set are 5, four with individual contacts for each position, one for the meter, two for the speaking conductors and the other for testing. The fifth contact consists of one contact in the normal position and a continuous metal plate extending through the other 24 positions.

According to the present invention this plate is replaced by two thinner plates insulated so that the total thickness of plates and insulation is approximately the same as for a single plate. One of these plates is earthed as hitherto, while the other plate is connected to a lead extending over the bank contacts of the cut-off and line relays to the rotary magnet. When the switch is in an off normal position, these two plates are bridged together by a single wiper.

When a call is initiated, line relay L is energized over the subscriber's negative and positive speaking conductors and operates its armatures X and Y, armature X being arranged to make contact before Y and to connect one side of the driving magnet to the test wiper P. Armature Y connects earth to one side of the switching relay K and also to the private normal wiper PN as well as wiper P. The connection of earth potential to wiper PN guards the test conductor P' since the bank contacts engaged by wipers P and PN in home position are strapped together and complete an energizing circuit for the driving magnet DM which accordingly energizes and de-energizes to advance the wipers from home position into engagement with the next set of bank contacts.

As soon as wiper PN advances from home position, it bridges the earth plate EP and the homing plate HP together. The incoming test conductor P' is now guarded and remains guarded all the time the switch is in an off-normal position over wiper PN from the earthed plate EP. If the contact engaged by wiper P is idle, switching relay K will energize in series with the driving magnet DM and switch the talking conductors through to the selected line.

Assuming however that the first set of bank contacts engaged by the wipers are busy, there will be an earth potential on the contact engaged by wiper P which will short circuit relay K and complete an energizing circuit for magnet DM which will as before energize and de-energize to advance the wipers to a fresh set of bank contacts. This operation will continue until an idle set of bank contacts is found whereupon switching relay K energizes. Switching relay K, upon energizing, connects the negative and positive speaking conductors through to the negative and positive wipers and disconnects the energizing circuit for relay L at armatures K'

and K². Relay L being slow to release does not fall away at once and relay K is held energized over armature Y. When the line and release relays of the selected switch energize, the latter relay connects earth to the bank contact engaged by wiper P and this earth potential serves to hold relay K energized over armature K³ after relay L de-energizes, as it will shortly after the opening of its energizing circuit.

Relay K, at armature K⁴, opens a point in the homing circuit of magnet DM and prepares a circuit for the meter M'. Relay L, upon de-energizing, removes earth potential at armature Y from the contacts engaged by wipers P and PN in home position, and armature X prepares a point in the homing circuit. The meter M' is operated in series with the driving magnet DM when earth potential is connected to the contact engaged by wiper M and upon energizing operates and closes a locking circuit for itself.

It will be seen that should an attendant operate relay L manually at a time when relay K is in operated position that such operation will have no effect upon the meter M'. The switch is released when earth potential is removed from the contact engaged by wiper P which brings about the de-energization of relay K. With relay K and relay L in deenergized position the following circuit is completed for driving magnet DM: battery, driving magnet DM and its interrupter contacts, K⁴ and its back contact, armature X and its back contact, homing plate HP, wiper PN, earth plate EP. This circuit persists until the wiper PN reaches home position, when the connection with the earth plate EP and the home plate HP is broken.

It will be seen that during the time that the switch is returning to normal, test conductor P' is guarded, thereby preventing the connector from seizing the line associated with the line switch until the line switch has returned to its home position.

On an incoming call, that is, when the line associated with the line switch shown is seized by a connector, switching relay K energizes over the following circuit: earth on the test wiper of the connector, conductor P', wiper PN in home position, winding of relay K, interrupter contacts and driving magnet DM to battery. Relay K alone energizes in this circuit and disconnects the normal battery and earth potentials from the negative and positive speaking conductors.

Referring to Figure 1, the private normal PN is connected to the homing wiper H so that when the line relay picks up, it is earthed through the first contact 1. The rotary line switch begins to rotate in the usual way due to the completion of a circuit from the private wiper P over contact 2, contact 3, rotary magnet DM to battery. The starting earth is

received over contacts 4 and 5. The advance of the switch is then automatic until the private wiper P fails to receive earth back, whereupon the cut off relay K energizes in known manner. As soon as the first step is made, the private normal receives an earth permanently from the lower plate LP.

It will be seen that when the calling party hangs up at the end of a conversation, the 10 private normal PN remains earthed from the lower plate LP, and when relay K de-energizes, due to guarding potential being removed from test wiper P by the switch ahead, the following circuit is completed for 15 the driving magnet: earth, plate LP, wiper H, plate HP, contact 6, contact 7, interrupter contacts rotary magnet DM to battery. The rotary magnet now rotates automatically due to the homing plate HP being 20 linked to the lower plate LP by the wiper H. The rotary magnet therefore rotates automatically until the wiper H reaches the home contact 1. It will thus be appreciated that by this means the private normal is effectively earthed all the time the rotary line 25 switch is returning to normal, and in fact all the time that the rotary line switch is off normal.

Referring now to Fig. 2, this arrangement 30 involves no modification of the contact bank as in Figs. 1 and 3. In this case, a slight modification is made to the meter leads, the meter being normally connected to earth when the cut-off relay is de-energized, there- 35 by giving a very reliable assurance that the meter cannot be operated falsely. For this purpose the normal connection from the private normal PN may be traced as follows: PN, cut off relay K, contact 1, wiper H, contact 7, rotary magnet DM to battery. If however the switch is in the off-normal position, the completion of the circuit for the cut-off relay is dependent upon the energization of either the line relay over contact 8 40 or the cut-off relay over contact 9. Consequently, if the cut-off relay de-energizes and the switch is in an off-normal position and the line relay is also de-energized the circuit of the relay K is opened at the points 9, 8, 45 and 1 and therefore the private normal is disconnected, and no circuit can be completed thereover until the switch returns to normal, when a circuit over contact 1 is completed. Earth is only connected to the common plate 50 CP engaged by the homing wiper H when the cut-off relay de-energizes. Consequently, one terminal of the meter is normally earthed.

Other modifications will readily occur to those versed in the art, for instance, as an 55 alternative to the first case, off-normal springs may be provided instead of the plates or the homing wiper may be divided into two components, while as an alternative to the other case other circuits will readily occur 60 to those versed in the art, but it is believed

that the circuit shown is the one requiring the least number of contacts additional to that previously required in circuits where the prevention of the operation of the cut-off relay was not complete.

Having now particularly described and ascertained the nature of my said invention, and in what manner the same is to be performed, I declare that what I claim is:

1. In a telephone system, a rotary line 75 switch of the homing type, a cut-off relay and a driving magnet in said switch, an incoming test conductor, a circuit including said conductor, said magnet, and said cut-off relay, and means for opening said circuit 80 for rendering said cut-off relay inoperable thereover whenever said switch is off-normal.

2. In a telephone system, a rotary line 85 switch of the homing type, a cut-off relay and a line relay in said switch, a bank comprising two insulated sections, a wiper for said switch for bridging said sections whenever said switch is off-normal, a driving magnet, and a homing circuit for said magnet including said wiper, said two insulated sections, 90 contacts on said cut-off relay, and contacts on said line relay in series.

3. In a telephone system, a homing type 95 rotary line switch, an incoming test conductor for said switch, and a wiper for placing on said conductor an idle test potential when said switch is in normal position and a busy test potential whenever said switch is off normal.

4. In a telephone system, a rotary line 100 switch of the homing type, a switching relay for said line switch, a bank contact normally connected to said switching relay, a magnet for operating said line switch to an off-normal position, an incoming test conductor, and a wiper for said switch adapted to place direct ground potential on said conductor and said contact whenever said switch is in an off-normal position.

5. In a telephone system, a rotary line 105 switch of the homing type, a switching relay for said line switch, a bank contact normally connected to said switching relay, a magnet for operating said line switch to an off-normal position, an incoming test conductor, a wiper for said switch adapted to place ground potential on said conductor and said contact whenever said switch is in an off-normal position, and a circuit including said wiper for operating said magnet to return 110 said switch to home position.

6. In a selector switch having a home position, two wipers insulated from each other, a circuit including one of said wipers for starting said switch, a circuit including the other of said wipers for restoring said switch, and a circuit including one of said wipers for marking said switch engaged whenever said switch is not in home position.

7. In a selector switch having a normal po- 130

sition, two wipers insulated from each other, means including one of said wipers for starting said switch and for testing trunk lines accessible to said switch, and means including the other of said wipers for restoring said switch and for marking said switch engaged whenever said switch is in an off-normal position.

8. In a telephone system, a rotary line switch of the homing type, means for causing the rotary movement of the switch, an incoming test conductor, a wiper terminating said conductor, a home position contact therefor, and a cut off relay controlled over the incoming test conductor, the wiper and the home position contacts simultaneously.

9. In a telephone system, a rotary line switch of the homing type, a cut off relay permanently connected to a bank contact, an incoming test conductor, and a circuit including the incoming test conductor and a wiper of the switch in series for operating the cut off relay.

10. In a telephone system, a rotary line switch of the homing type, a cut off relay, an incoming test conductor, and a circuit including the incoming test conductor and a wiper of the switch in series for operating the cut off relay, the said switch wiper constituting means for preventing the operation of the cut off relay when the switch is returning to the home position.

11. In a rotary line switch of the homing type, a cut off relay, an incoming test conductor, a wiper, a circuit for energizing said relay established under certain conditions and extending through said test conductor and said wiper when the wiper is in the home position, and a circuit for energizing said relay established under other conditions and excluding said wiper.

12. In a rotary line switch, a cut off relay, two wipers, and two circuits for operating said relay, each extending through a different one of said wipers.

13. In a rotary line switch, a cut off relay, two wipers, two circuits for operating said relay, each extending through a different one of said wipers, and a third circuit for operating said relay excluding both of said wipers.

14. In a rotary line switch of the homing type, a cut off relay, an operating circuit and a holding circuit for said cut off relay closed successively during the establishment of an outgoing call, a third circuit for said cut off relay completed during the establishment of an incoming call, and means for opening said third circuit whenever said switch is in an off-normal position.

15. In a telephone system, a line, a rotary line switch for said line, a cut-off relay in said switch, a circuit including a wiper of said switch for energizing said relay on incoming calls to said line, and means for dis-

connecting said relay from said wiper whenever said switch is off-normal.

16. In a telephone system, a line, a rotary line switch for said line, a cut-off relay in said switch, a home position contact in the switch-bank of said switch permanently connected to said relay, a wiper normally engaging said contact, and a circuit including said wiper and said contact in series for energizing said relay on incoming calls to said line.

17. In an automatic hunting switch, two wipers, two home position bank contacts engaged by said wipers, respectively, a conductor connecting said bank contacts, and a circuit including said conductor and said wipers for starting the hunting movement of the switch.

18. In a rotary line switch of the homing type, a line relay, two wipers, an incoming test conductor, a stepping magnet, and contacts on said line relay for connecting a source of current through one of said wipers to said conductor to make the switch busy and through the other of said wipers to said magnet to cause the operation thereof.

19. In an automatic switch, a wiper, a conductor terminating therein, two bank contacts engaged by said wiper simultaneously, a circuit extending through said conductor, said wiper and one of said bank contacts, and another circuit extending through said wiper and both bank contacts but not through said conductor.

20. In a homing type rotary line switch, a wiper, an incoming test conductor permanently connected to said wiper, and a cut-off relay energized over said conductor and wiper in series.

21. In a homing type rotary line switch, a wiper, an incoming test conductor terminating in said wiper, and a cut-off relay connected to a bank contact normally engaged by said wiper but disengaged therefrom whenever the switch is off-normal.

22. In a homing type rotary line switch, a wiper, an incoming test conductor terminating in said wiper, a cut-off relay normally connected to said conductor through said wiper but disconnected therefrom whenever the switch is off-normal, and a permanently grounded bank contact engaged by said wiper whenever said switch is off-normal.

23. In a rotary line switch of the homing type, a cut-off relay, an incoming test conductor, a wiper, a circuit extending through said test conductor and said wiper for energizing said relay in incoming calls, and a circuit excluding said wiper for energizing said relay in outgoing calls.

In witness whereof, I hereunto subscribe my name this 19th day of May A. D. 1926.

JOHN E. OSTLINE.
